(57) **CLAIM**

The ornamental design for a turtle handheld flotation device, as shown and described.

DESCRIPTION

FIG. 1 is a front, top, perspective view of a turtle handheld flotation device, showing my new design.

FIG. 2 is a top plan view thereof.

FIG. 3 is a bottom plan view thereof.

FIG. 4 is a left side elevation view thereof.

FIG. 5 is a right side elevation view thereof.

FIG. 6 is a front elevation view thereof; and,

FIG. 7 is a back elevation view thereof.

The surfaces are lightly lined for contour.
